UNITED STATES PATENT OFFICE.

ALFRED A. ZIEGLER, OF BOSTON, MASSACHUSETTS.

SIGNAL-LANTERN.

1,290,471.

Specification of Letters Patent.

Patented Jan. 7, 1919.

Application filed November 6, 1915. Serial No. 60,105.

To all whom it may concern:

Be it known that I, ALFRED A. ZIEGLER, a citizen of the United States, residing at Boston, in the county of Suffolk and State of Massachusetts, have invented an Improvement in Signal-Lanterns, of which the following is a specification.

This invention relates to electric illuminating units, and is intended as an improvement on the device of Letters Patent #1,173,239, dated Feb. 29, 1916, granted to me.

One of the objects of the invention is to improve the construction and arrangement of the lamp-block, and associated members, so that said block with its associated members, may be assembled as a unit and applied to or removed from the base-block.

Another object is the provision of binding-posts for the leading-in wires, and means associated with the lamp-block for supporting one or both binding-posts.

Another object of the invention is the provision of passages in the base-block for the circuit-wires which lead to the lamp-sockets.

Referring now to the drawing,

Figure 1 is a side elevation of an electric railway signal lantern embodying my invention, the door of the casing being raised to disclose the manner in which the lamps and associated parts of the illuminating unit are arranged therein.

Fig. 2 is a detail view, in side elevation, of the lamps, supporting means therefor and automatic circuit-controlling means for the lamps.

Fig. 3 is a plan view of the device shown in Fig. 2.

Fig. 4 is a section on the line 4—4 of Fig. 3.

Fig. 5 is a bottom plan view of the lamp block.

Fig. 6 is a section on the line 6—6 of Fig. 5.

Fig. 7 is a top plan view of a modified form of the invention.

Fig. 8 is a longitudinal vertical section of one of the binding posts.

Fig. 9 is a diagrammatical view of the circuits employed in the modified form of the invention, shown in Fig. 7.

Primarily, my invention involves an improved electrical illuminating unit, but, in order that the use of the device may be understood, I have herein illustrated the same as applied to a railway signal-lantern, as in

the aforesaid application. This lantern includes a casing or housing A, having a sliding door B, and a lens C, and an electric illuminating unit D, arranged in the casing A. 60 Said unit comprises two lamps L and L^a, adapted to be placed in lamp-sockets arranged on a lamp-block F, which is removably mounted on a base-block E, an associated automatic circuit-controlling mechanism G, for the lamps being also mounted on the base-block, and so arranged that in the event of failure of one of the lamps, the other is instantaneously and automatically introduced into the lighting-circuit. 70

The base-block E, usually of wood, is here shown as, rectangular in general outline, and as here shown a pair of upwardly converging passages 10 and 11 are formed therein to accommodate the circuit-wires which lead to 75 the binding-posts. The passage 11 extends from a point at the approximate center of the bottom-face of the block to the upper face thereof and adjacent one end, being located between the binding-posts H and K. 80 The other passage 10 leads from one corner of the block into the passage 11 adjacent to the upper end thereof.

The lamp-block F, of insulating material, is here shown as rectangular in general outline, and composed usually of porcelain. In the upper face of the lamp-block are arranged two lamp-sockets 12, see Fig. 4. The upper end of each of the sockets is or may be defined by an annular lip 13. The bottom face of the lamp-block is provided with a pair of substantially L-shaped grooves 14 and 15, wherein are seated, or otherwise arranged, conductor-strips 16 and 17.

The transverse portion of the groove 15 95 has a relatively deep recess 18, see Fig. 6, wherein is arranged an offset portion 19 of the conductor-strip 17, said offset portion enabling the two conductor-strips to intersect upon the bottom of the block without 100 engaging each other; and an attaching-screw 21 extends through the block and offset-portion to attach the strip thereto. One end of the strip 17 extends transversely along the underside of the block and is upturned at the rear side thereof, and bears a binding-screw 21^a for a circuit-wire. As shown in Figs. 1 and 5, both strips are extended laterally from the block and are attached at their extremities to the base-block 110 by screws or other means. There is an offset-portion 20 formed in each extension, near

its extremity, adapted to receive the head of the screw of a binding-post, which posts are indicated at H and K, so that said posts may be associated with the block.

5 The strip 16 is attached to the block by a pair of contact-screws 22 and 23, the heads of which are located in the bottoms of the lamp-sockets 12, see Fig. 4, so that not only is the strip held in place but is electrically connected to one terminal of both of the lamps. Said screws extend downwardly through the lamp-block and base-block and terminate in recesses 24, and receive upon them nuts 25 which are concealed by insulating sealing means.

10 The screws 22, 23, are insulated from the metallic socket-sleeves 27, by insulating gaskets 28. Metal washers 29 may be interposed between the gaskets and the heads 20 of the screws. As terminal-connectors for the other side of the lamps, the metallic sleeve-members 27 and 27^a, have ears 30, which extend laterally through openings 31 in the sockets, and bear binding-screws for 25 the circuit-wires, as shown in Fig. 3. In the sleeve of each lamp-socket, is a removable spring contact-element indicated at 32.

15 The modified form of my invention shown in Fig. 7 is similar in general construction to the preferred embodiment, except as to the arrangement of the lamp-block 70 upon the base of the supporting-member 71, and the arrangement of the binding-posts and conductor-strips thereof. The lamp-block 30 70, wherein are formed the lamp sockets 72 and 73, similar to the sockets 12 and 13, is mounted longitudinally upon the base 71 and extends in right angles to the conductor-frame 74 in which the automatic circuit-controlling means, generally designated by 35 the letter m, is mounted. On opposite sides of the block 70 are disposed the binding-posts 75 and 76, which members are similar to the binding-posts of the preferred form 40 and are secured by screws or equivalent fastening-means 77. The binding-post 76 is electrically connected to the conductor-plate 78, which is equivalent to the conductor-plate 39, by a wire 79, the conductor-strip 45 17 being absent in this modified form of the invention. A conductor-strip, indicated at 80, which is similar to the member 16 and is secured in the lamp-block 70 in a similar manner, electrically connects the binding-post 75 with the conductor-screws of the 50 sockets 72 and 73. The conducting strips 81 and 82 of the sockets 72 and 73 are respectively connected by wires 83 and 84 to the plate 78 and the conductor-frame 74.

55 60 The operation of the modified form of Fig. 7 will be readily appreciated upon reference to the wiring diagram of Fig. 9.

The binding-posts H, K, 75, and 76, are all, as stated, of similar construction, and 65 are preferably of the type illustrated in

the detail in Fig. 8. As shown in this figure, the binding-post includes a base-plate 85, the intermediate portion of which is offset or bent into a substantially U-shaped loop 86, wherein the head 87 of the screw 70 88 is seated, and through which the screw passes upwardly. A bottom nut 89 is set upon the screw, and upon this nut are disposed a pair of washers 90, and above said washers clamping nuts 91 and 92 are arranged.

I claim:—

1. In an electric illuminating-unit, a base-block, a lamp-block thereon, a lamp-socket arranged on the lamp-block, a conductor-strip attached to the lamp-block and supported thereby and electrically connected to the lamp-socket, one end of said strip being extended laterally from the lamp-block, above the base-block and detachably secured, 80 at its end thereof, to said base-block, and a binding-post connected to the laterally extended end of said conductor-strip intermediate its length, said lamp-block, conductor-strip, and binding-post being assembled 85 as a unit, and arranged on said base-block.

2. In an electric illuminating-unit, a base-block, a lamp-block, lamp-sockets arranged on the lamp-block, a conductor-strip attached to the lamp-block and electrically 90 connected to the sockets, a second conductor-strip attached to said lamp-block and insulated from said lamp sockets, and one end of each of said strips being extended laterally beyond the lamp-block, binding-posts 95 carried by the extensions of said strips intermediate the lengths thereof, said lamp-block, conductor-strips, and binding-posts, being assembled as a unit, and arranged on the base-block.

105 3. In an electric illuminating-unit, a base-block, a lamp-block, a pair of lamp-sockets integrally formed with said lamp-block, a conductor-strip attached to the lamp-block and supported thereby and electrically connected to both of said sockets, another conductor-strip attached to the lamp-block and supported thereby and insulated from the aforesaid conductor-strip and said lamp sockets, both of said strips being extended 110 laterally from the lamp block above said base-block, and a binding-post borne by each of said conductor-strips, intermediate the laterally extended ends thereof, said lamp-block, conductor-strips and binding-posts 115 being all assembled as a unit, and secured to said base-block.

120 4. In an electric illuminating-unit, a base-block, a lamp-block, a lamp-socket arranged on the lamp-block, a conductor-strip attached to the lamp-block and electrically connected to the lamp-socket, one end of said strip being extended laterally beyond the lamp-block above said base-block and having an end-portion by which said lateral ex- 125 130

tension is attached to the base-block, and a binding-post connected with the laterally extended end of the conductor-strip intermediate said lamp-block and said end portion, said lamp-block, conductor-strip, and binding-post being assembled as a unit, and secured to said base-block.

5. In an electric illuminating-unit, a base-block, a lamp-block, lamp-sockets arranged 10 in the lamp-block, conductor-strips attached to and supported by said lamp-block, only one of which strips is in electrical connection with said sockets, one end of each of said strips being extended laterally beyond 15 the lamp-block above said base-block and arranged to be attached to the base-block at the ends of said end portions, and binding-posts carried by the extensions of said strips, intermediate said lamp-block and said ends 20 of said strips thereof, said lamp-block, conductor-strips, and binding-posts being assembled as a unit, and secured to the base-block.

6. In an electric illuminating unit, a base-block, a lamp-block, lamp-sockets arranged 25 on the lamp-block, a substantially L-shaped unitary conductor-strip attached to and supported by the lamp-block and electrically connected to both lamp-sockets, another conductor-strip attached to the lamp-block and insulated from said lamp sockets and said first conductor-strip having a binding-screw at one end, and a binding-post mounted upon and borne by each conductor-strip, said 30 lamp-block, conductor-strips, and binding-posts being assembled as a unit, and adapted 35 for arrangement on the base-block.

7. In an electric illuminating-unit, a base-block, a lamp-block, a lamp-socket arranged 40 in the lamp-block, a conductor-strip attached to the lamp-block and electrically connected to the lamp-socket, one end of said strip being extended laterally from the lamp-block, and having an offset portion, 45 and a binding-post arranged on said off-set portion with the head of its screw arranged in the recess formed thereby, and means arranged on said strip beyond said offset portion to detachably secure said strip to said 50 base-block.

8. In an electric illuminating-unit, a base-block, a lamp-block, a lamp-socket arranged in the lamp-block, a conductor-strip attached to the lamp-block and electrically 55 connected to the lamp-socket, one end of said strip being extended laterally from the lamp-block, and means carried by the extremity of said strip to detachably secure said strip to the base-block, an off-set portion intermediate the length of said lateral 60 extension, and a binding-post arranged on

said off-set portion with the head of its screw arranged in the recess formed thereby.

9. In an electric illuminating-unit, a base-block, a lamp-block mounted thereon, lamp- 65 sockets arranged in said lamp-block, a conductor-strip arranged at the bottom of the lamp-block and extended laterally therefrom, and a terminal arranged at the bottom of each socket, and provided with an end- 70 portion by means of which said strip is secured to said base-block, said terminals being extended through the lamp-block, conductor-strip, and base-block, and having nuts arranged upon them for holding the 75 parts assembled.

10. In an electric illuminating unit, a base block, a lamp block, lamp sockets arranged in said lamp block, terminals passing through said sockets and base block, one or 80 more conducting strips electrically connected with said lamp sockets by means of said terminals and extended from said sockets and adapted to support the binding-posts and having end-portions whereby said extensions of said strips are secured to said base-block, and binding-posts on said strips, all 85 said parts being assembled as a unit and adapted to be arranged upon and detachably connected with the base block. 90

11. An electric illuminating unit including a lamp-block having a pair of lamp sockets integrally formed therewith, a base-block to which said lamp-block is secured, screws arranged within said lamp sockets 95 and passing through said lamp and base-block, by which means said lamp-block is secured to said base-block, a conductor extending between said blocks and making contact with a terminal of said lamp sockets 100 and having a laterally extending portion extending over said base-block and having the end-portion thereof detachably secured to said base-block, binding means on said end-portion, a second conductor, insulated from said first conductor and said lamp sockets, extending between said blocks, one end of 105 which projects beyond said lamp block on one side and terminates in binding means, and the other end portion of which projects beyond the other side of said lamp-block and is detachably secured to said base-block, and binding means on said last-named end-portion. 110

In testimony whereof, I have signed my 115 name to this specification in the presence of two subscribing witnesses.

ALFRED A. ZIEGLER.
